UNITED STATES PATENT OFFICE.

JOHN GRAVES, OF NEW YORK, N. Y.

CLOSURE FOR JARS OR THE LIKE.

SPECIFICATION forming part of Letters Patent No. 783,116, dated February 21, 1905.

Application filed August 26, 1904. Serial No. 222,234.

To all whom it may concern:

Be it known that I, JOHN GRAVES, a citizen of the United States, residing at New York city, county of New York, and State of New York, 5 have invented certain new and useful Improvements in Closures for Jars or the Like, fully described and represented in the following specification and the accompanying drawings, forming a part of the same.

10 This invention relates to improvements in closures for jars or the like.

Closures for jars or the like as heretofore constructed, which are simple in construction, cheaply manufactured, and readily manipulated, are open to the objection of not effecting an air-tight closure, thereby rendering the contents subject to the disadvantages caused by atmospheric conditions and also making it possible if the jar should be upset 15 for the contents, in some cases at least, to gradually leak out.

The present invention has for its object to provide a closure for jars or the like which shall be simple in construction, cheaply manufactured, and readily manipulated and at the 20 same time when in position thereon effect an air-tight closure of the jar or the like.

As a full understanding of the improvements constituting the present invention can 25 best be had from a detailed description of an organization embodying the same, such description will now be given in connection with the accompanying drawings, in which—

Figure 1 is a sectional view of the neck of 30 a jar provided with my improved closure. Fig. 2 is a plan view thereof, and Fig. 3 is a side view of a grooved strip hereinafter described.

Referring to said drawings, A represents 35 the upper part of an ordinary jar, and 1 a disk, preferably formed of cardboard, of a size to cover the mouth of the jar or the like, which disk may, if desired, have a covering 10 of felt or other suitable material on its face, 40 which will afford resiliency in the closing operation, and thereby insure a very tight closure. When this covering 10 of felt is used, a further covering 2 of enameled cloth or other suitable material is placed over the covering 45 10 of felt for the purpose of preventing the

contents of the jar from coming in contact with the covering 10 of felt.

3 represents a short piece of stiff wire or other suitable material bent at its center to preferably an obtuse angle 4, the ends of 55 which wire being also bent so as to conform substantially to the shoulder 5 on the neck of the jar and disk 1 when placed over the mouth thereof and to terminate in hooks 6, adapted to be hooked under said shoulder 5, and thereby prevent said wire 3 from upward movement. The angle 4 of this wire 3 is adapted to set in a groove 7, formed in the upper edge 9 of a narrow strip 8 of wood or other suitable material, said upper edge 9 of this strip 8 60 preferably being formed to slope in a direction from the groove 7, so that the edge adapted to rest on the disk 1 will be of a length equal to the diameter of said disk 1 and said strip 8 also being of a height to fit snugly between 65 the disk 1 and the angle 4 of the wire 3 when set in the groove 7 thereof, thereby causing said disk 1 to be pressed firmly on the mouth of the jar or the like, as shown in Fig. 1.

To close a jar or the like with my improved 70 form of closure, the disk 1 is placed over the mouth of the jar, the hooks 6, formed at the ends of the wire 3, then placed under the shoulder 5, formed on the neck of the jar, and the grooved strip 8 then placed sidewise 80c on the disk 1 and raised on its lower edge, with the wire 3 in the groove 7, until the strip 8 is in an upright position, with the angle 4 of the wire 3 resting in the groove 7, as shown 75 in Fig. 1.

To open a jar having my improved form of closure, the lower part of the side 11 of the strip 8 is pressed against until it gives way.

What I claim is—

1. In a closure for jars, the combination with 90 a shoulder formed on the neck of the jar, a disk of a size to cover the mouth of said jar, a layer of felt with a protective covering of enameled cloth attached to the face of said disk, a bar formed with an angle at its center, the ends 95 of which being also formed to provide hooks adapted to hook under said shoulder, and a binding-strip with a groove in the center of its upper edge in which the angle of said bar is adapted to rest when said strip is in an upright 100

or binding position, said strip being of a height to fit tightly between the disk and bar when in binding position, substantially as described.

2. In a closure for jars, the combination with 5 a shoulder formed on the neck of the jar, a disk of a size to cover the mouth of said jar, a layer of felt with a protective covering of enameled cloth attached to the face of said disk, a bar formed to provide hooks at its ends adapted 10 to hook under said shoulder, and a binding-strip with a groove in the center of its upper edge in which said bar is adapted to rest when said strip is in an upright or binding position, said strip being of a height to fit tightly between the disk and bar when in binding position, substantially as described.

3. In a closure for jars, the combination with 20 a shoulder formed on the neck of the jar, a disk of a size to cover the mouth of said jar, a layer of felt with a protective covering of enameled cloth attached to the face of said disk, a bar formed with an angle at its center, the ends of which being also formed to provide hooks adapted to hook under said shoulder, and a 25 binding-strip of a height to fit tightly between the disk and bar when in binding position, substantially as described.

4. In a closure for jars, the combination with 30 a shoulder formed on the neck of the jar, a disk of a size to cover the mouth of said jar, a layer of felt with a protective covering of enameled

cloth attached to the face of said disk, a bar formed to provide hooks at its ends adapted to hook under said shoulder, and a binding-strip of a height to fit tightly between the disk 35 and bar when in binding position, substantially as described.

5. In a closure for jars, the combination with 40 a shoulder formed on the neck of the jar, a cardboard disk of a size to cover the mouth of said jar, a layer of felt with a protective covering of enameled cloth attached to the face of said disk, a bar formed with an angle at its center, the ends of which being also formed to provide hooks adapted to hook under said shoulder, and 45 a binding-strip with a groove in the center of its upper edge in which the angle of said bar is adapted to rest when said strip is in an upright or binding position, said strip being of a height to fit tightly between the disk and bar 50 when in binding position, thereby causing said disk with its said coverings to be pressed tightly against and conform to any irregularities upon the neck of said jar, substantially as described.

In testimony whereof I have hereunto set my hand in the presence of two subscribing witnesses.

JOHN GRAVES.
